GOLF PUTTER

Patrick J. Rose, 25 Royal Oak Drive,
West Hartford, Conn. 06107

Filed Mar. 28, 1968, Ser. No. 11,183

Term of patent 14 years

(Cl. D34—5)

FIG. 1 is a front view in perspective of one embodiment of a golf putter embodying my new design;

FIG. 2 is a fragmentary rear view in perspective of the same;

FIG. 3 is a cross-sectional view taken along the line 3—3 of FIG. 2;

FIG. 4 is a bottom view thereof; and

FIG. 5 is a fragmentary front view in perspective of a second embodiment of a golf putter embodying my new design wherein a bent or goose-neck hosel is employed

The features of my design sought to be patented reside in the portions shown in full lines.

I claim:

The ornamental design for a golf putter, as shown and described.
